United States Patent [19]

Birrell et al.

[11] Patent Number: Des. 313,826

[45] Date of Patent: ** Jan. 15, 1991

[54] EXERCISE TREADMILL

[75] Inventors: James S. Birrell, Seattle; Timothy O. Armstrong, Bellevue; Kenneth G. Real, Redmond; Gary M. Bang, Edmonds, all of Wash.

[73] Assignee: Precor Incorporated, Bothell, Wash.

[**] Term: 14 Years

[21] Appl. No.: 254,793

[22] Filed: Oct. 12, 1988

Related U.S. Application Data

[63] Continuation-in-part of Ser. No. 102,201, Oct. 2, 1987, Pat. No. D. 303,414.

[52] U.S. Cl. D21/194

[58] Field of Search ..... D21/191-199; 272/69, DIG. 6; 119/29

[57]

CLAIM

The ornamental design for an exercise treadmill, as shown and described.

DESCRIPTION

FIG. 1 is a perspective view of an exercise treadmill showing our new design;

FIG. 2 is a side elevational view thereof;

FIG. 3 is a side elevational view thereof;

FIG. 4 is a top plan view thereof;

FIG. 5 is a bottom plan view thereof;

FIG. 6 is a front elevational view thereof; and,

FIG. 7 is a rear elevational view thereof.

*Fig. 1.**Fig. 2.*

*Fig. 3.**Fig. 4.**Fig. 5.*

*Fig. 6.**Fig. 7.*
